U.S. Appl. No. 15/849,061, filed Dec. 20, 2017.

Primary Examiner — Karen E Kearney*Assistant Examiner* — Lilyana Bekic(74) *Attorney, Agent, or Firm* — Cohen & Hildebrand, PLLC(57) **CLAIM**

The ornamental design for a neck plate for tracheal tube, as shown and described.

DESCRIPTION

FIG. 1 is a front perspective view of the neck plate for tracheal tube;

FIG. 2 is a bottom perspective view of the neck plate for tracheal tube;

FIG. 3 is a back perspective view of the neck plate for tracheal tube;

FIG. 4 is a front view of the neck plate for tracheal tube;

FIG. 5 is a side view of the neck plate for tracheal tube; and,

FIG. 6 is a top view of the neck plate for tracheal tube.

The broken lines in the drawings depict portions of the neck plate for tracheal tube that form no part of the claimed

design.
